United States Patent Office.

JOHN T. BAILEY, OF PHILADELPHIA, PENNSYLVANIA, ASSIGNOR TO HIMSELF AND JAMES CASCADEN, OF SAME PLACE.

Design No. 2,819, dated November 5, 1867.

DESIGN FOR A TRADE-MARK.

The Schedule referred to in these Letters Patent and making part of the same.

TO ALL WHOM IT MAY CONCERN:

Be it known that I, JOHN T. BAILEY, of Philadelphia, county of Philadelphia, State of Pennsylvania, have invented or produced a new and original Design for a Trade-Mark; and I do hereby declare that the accompanying drawing, and the following explanation thereof, form a full, clear, and exact description of the said design.

In the accompanying drawing, A represents a bag, on the centre of which are the words "Star Mill," "Seamless."

I claim the design for a trade-mark, substantially as represented in and by the accompanying drawing. In testimony whereof I have signed my name to this specification in the presence of two subscribing witnesses.

Witnesses:

CHARLES E. FOSTER,
W. J. R. DELANY.
